UNITED STATES PATENT OFFICE.

GEORGE W. LORIMER, OF TROY, AND JAMES MCVICKER, OF CHILLICOTHE, OHIO, ASSIGNEES, BY DIRECT AND MESNE ASSIGNMENTS, TO BINGHAM-LORIMER MANUFACTURING COMPANY, A CORPORATION OF DELAWARE.

TARGET TRAP.

Application filed February 9, 1924. Serial No. 691,682.

This invention relates to an automatic trap, and more particularly to a form of trap for throwing clay targets, and the like.

One of the principal objects of the invention is to provide an automatic trap for throwing targets, which is constructed to automatically vary the angles at which the targets are thrown, and is at the same time so constructed that this variation in the angles is not subject to any set succession, but is indeterminate.

Another object of the invention is to provide a mechanism of this character which is simple in construction, durable and accurate in operation, and independent in its angle varying of manual setting or adjustment.

Other objects and advantages of the invention will be apparent from the description thereof set out below when taken in connection with the accompanying drawing.

In the drawing in which like characters of reference designate like parts throughout the several views thereof,

Fig. 1 is a vertical sectional view, with certain parts shown in elevation, of a trap embodying this invention;

Fig. 2 is a plan view of the base portion of the device as shown in Fig. 1;

Fig. 3 is a plan view of the target throwing mechanism shown in Fig. 1;

Fig. 4 is a fragmentary plan view of the target throwing mechanism with the parts in cocked position; and

Fig. 5 is a view similar to Fig. 2, but showing a slightly modified form of construction.

Machines have been heretofore devised for the throwing of targets such as the well known "clay pigeons", and in certain of these machines an effort has been made to provide for automatic variable setting of the mechanism so as to throw the targets at variable angles. But each of such devices heretofore known has been objectionable in that the variations in the angular positioning of the trap follow a definite sequence, so that one familiar with the mode of operation of the target trap can anticipate the direction in which the target is to be thrown. In the type of device described herein this objection is overcome by so constructing the angle varying mechanism of the trap as to place it under latent control and to introduce an indeterminate factor, so that the angle vary-

ing follows no definite sequence, and therefore, may not be "out guessed".

This trap consists of a base member or casting 10, adapted for rigid attachment to a suitable plank or other foundation, not shown, by bolts passing through bolt holes 11. Projecting downwardly from the base member, adjacent one end thereof, is a boss or projection 12, the boss, and the portion of the base member to which it is attached having a passage 13 therethrough. Pivottally mounted within passage 13 is the shank of 55 the pivot 15, the upper end of which is provided with an outstanding flange which forms a disc like head 16 thereon.

Slidably mounted upon the shaft 15 is a disc 17, which is provided with suitable slots 18, to receive the pin 19, mounted within the shaft; this construction being such that movement of the disc along the shaft is permitted, while the two are constrained to rotate together. Interposed between the 75 disc 17 and the cooperating upper face of the base member 10 is a layer or disc 20 of friction material. Around its upper outer edge the disc 17 is cut away as shown at 23 to receive the dog carrying plate 24. Rotatably mounted upon the pivot 15, and interposed between the disc 17 and the head 16 is a ratchet disc 25, a suitable layer of friction material 26 being interposed between the disc 17 and the ratchet disc 25, and a suitable layer of friction material 27 between the disc 25 and the head 16. These two friction discs 26 and 27 are preferably composed of material having a high coefficient of friction, such as sheet asbestos of the character used for automobile brake lining, sheet cork or the like and constitute what may be termed a control wheel. The layer 20 is also composed of a friction material but a material which has a substantially lower 90 coefficient of friction than two friction discs 26 and 27, such a material for instance as vulcanized fiber, or the like. Attached to the outstanding portion of the dog carrier 24 is a connecting rod 30, this rod being 100 pivotally connected to one end of the extension of the dog carrier and connected at its other end to the operating pull rod 31, so that as the rod 31 is pulled, in the operation of the mechanism, the dog carrier will pivot 105 about the disc 17. Pivotally mounted upon

the dog carrier is a dog 32, which is held by means of the spring 33, in contact with the teeth of the ratchet disc 25, so that as the dog carrier is moved in one direction it will 5 carry the ratchet disc with it, and through the instrumentality of the several friction discs, the positive movement imparted to the ratchet wheel will be imparted to the pivot and the parts carried thereby, through the 10 friction—and therefore yieldable—means. But reverse movement of the pivot, when the dog carrier is moved in the other direction, will be prevented, because of the frictional resistance due to the several friction 15 discs.

Extending upwardly from the upper face of the base of the member 10 is a hub 35, upon which is rotatably mounted the dog carrier 36. Mounted within the hub 35 is a 20 stud 37, upon the upper end of which is rotatably mounted the ratchet wheel 38, this wheel being of a diameter which is either greater or less than the diameter of the ratchet member 25, and having either a 25 greater or a less number of ratchet teeth. Connecting the dog carrier 24 to the dog carrier 36 is a connecting rod 40, which is pivotally connected at its opposite ends to the respective dog carriers. Pivotally 30 mounted upon the dog carrier 36 is a dog 41, which is held by means of the spring 42 in engagement with the ratchet teeth upon the ratchet disc 38. This dog is so arranged that as the pull bar is pulled to move the 35 dog carrier 24, and through the medium of the dog 32, to thus cause rotation of the ratchet disc 25, the dog carrier 36 will, through the medium of the dog 41, cause corresponding movement of the ratchet disc 38. Mounted upon the base member 10 is a 40 dog 43, which is also held in contact with the ratchet teeth upon the member 38 by means of a spring 44. And this dog 43 is arranged to act oppositely to dog 41, so that 45 while the dog 41 will cause rotation of the member 38, upon movement of the dog carrier 36 in one direction, the dog 43 will prevent reverse movement of the member 38 when the dog carrier is moved in the opposite 50 direction; it being understood that the friction and drag between the several parts is sufficient to cause the ratchet wheel 38 to oscillate back and forth with the dog carrier 36 when the pawl or dog 43 is out of operative contact with the teeth of the wheel 38.

Mounted rigidly upon the head 16 is a member 50, upon which is adjustably mounted the frame of the target throwing 60 portion of the mechanism. This member 50 is provided at one end with an extension 51, which, as shown in Fig. 2, is preferably curved, the curved portion 51 overlying the ratchet disc 38. Mounted upon the ratchet 65 disc 38, and out of diametrical alignment,

are two pins or studs 52 which are so positioned that as this disc is rotated these pins will be moved through a path which will bring them into contact with the extension 51. As the rod 31 is pulled, the actuating 70 bar 30 will cause each of the ratchet members 25 and 38 to rotate in the same direction. The construction and adjustment may be such as to cause each ratchet wheel to advance one, two, or any desired number of 75 teeth upon each pull of the operating bar. Preferably the arrangement is such that during operation each of these ratchet discs will be advanced three teeth upon each full pull of the bar 31. When the mechanism 80 is thus set up to advance the ratchet wheels three teeth on each pull, the number of teeth on each wheel should be uneven, in addition to providing one ratchet wheel with more teeth than the other. And preferably 85 the number of teeth on each ratchet wheel should not be evenly divisible by two or three. Because of the frictional resistance interposed the pivot shaft 15, and the member 50 carried thereby, will rotate in unison 90 with this pivot 15. As either of the pins 52 is brought into engagement with the extension 51, however, the frictional resistance between the two will be overcome and the shaft 15 will be caused to rotate in the opposite 95 direction, even though the other discs associated therewith should continue to rotate in the original direction.

Mounted upon the ratchet disc 25 is a cam member 55, which is arranged to contact with the extension 56, upon the dog 43, and is so constructed that as the ratchet disc 25 is rotated this cam will, during a part of the rotation of such ratchet disc, hold the dog 43 out of contact with the teeth of the ratchet member 38. When this dog is thus held out of operative engagement, the ratchet member 38 is free to move in either direction, as the dog carrier 36 is rotated, and it will remain thus free until such time 105 at the rotation of the ratchet member 25 carries the cam out of engagement with the dog 43 so as to permit that dog to drop into operative engagement with the teeth on the member 38, and prevent reverse movement 110 of that member.

Mounted upon the base 10 is an upstanding lug 57 within which is adjustably mounted a stop screw 58. This stop screw is positioned within the path of movement 120 of the other extended end 59 of member 50 to limit movement thereof in one direction.

The frame of the target throwing mechanism consists of a casting 60, which is provided with a slot 61, within which is slidably mounted a bar 62, which is held in the slot by means of suitable keepers 63. This frame is adjustably connected to the member 50. As shown it is pivotally connected at one end to the member 50 by means of a 130

suitable bolt 64, and is connected intermediate its length to the member 50 by means of a bolt 65, which is positioned within the arcuate slot 66, this construction being such that by loosening the nut of the bolt 65 the angular elevation of the frame 60 may be varied, within the operating range of the device.

The rear end of the bar 62 is connected to the pull rod 31 by means of a suitable pin connection, designated generally by the numeral 67. Connected to the bar 62 adjacent its front end is a projection 68, on which is mounted a roller 69. This roller is adapted to cooperate with one end of the cam 70, which is mounted upon the shaft 71, and is provided at its other end with a bolt 72. Pivotally connected to the bolt is an eye member 73 which is connected to one end of the main spring 74, the other end of the main spring being connected to the adjusting bolt 75, suitable manipulation of the nut 76 giving any desired tension of the main spring. Loosely mounted upon the shaft 71,

25 and on top of the frame 60, is the target carrier arm 80, which, as shown in Figs. 1 and 3, is of the chute type, and is provided with a spaced rail 81. A rubber facing strip 81' is carried by the rail and serves to increase the rotary motion given to the targets as they leave the arm thus adding to their stability of flight. This arm 80 is held snugly in place, and against the frame 70, by means of a coiled spring 82, the lower end 30 of which contacts with the pin 83 carried by the arm 80, and the upper end of which contacts with the pin 84, carried by the shaft 71.

Slidably mounted upon the frame 60 is a spring pressed latch 85, with which is associated a spring 86. Carried by this latch is a pin 87 which is adapted to cooperate with the trigger member 88. This trigger member 88 is pivotally mounted, at 90, upon the frame 60, and is provided at its lower end with an opening 91, which receives a pin 92, mounted in the keeper 63, which pin projects through the hole and limits pivotal movement of this trigger. Carried by the bar 62, at its forward end, is a projection 95, which, cooperates with the trigger member to cause actuation thereof.

Pivotally mounted upon the frame 60 are two curved fingers 98, which are so positioned that when the carrier arm is in cocked position these fingers may be swung across the arm to hold the targets in position. Two fingers are provided so that one or both may be used according as it is desired to throw one or two targets at a time.

60 In the operation of the device, the pull rod 31 is pulled by the attendant, and carries with it the bar 62, sliding that bar within the frame. As this bar thus slides the roller 69 contacts with the cam 70 and carries that cam with it thus rotating the shaft 71. As

the shaft 71 rotates, the arm 80 is correspondingly moved to bring the latch 89, at the front end thereof into latching engagement with the latch 86, the proportions of the parts being such that the latch 85 will overlie the latch 89 only a short distance. The amount of pull that should be given to the rod 31, to accomplish this setting or cocking, of the mechanism is preferably controlled by means of a regulating screw or other form of adjustable stop, which is located at the puller's station. But if for any reason this regulating screw should not be properly adjusted the pulling strain cannot injure the trap as the sliding bar will merely continue to slide 70 within the frame 60. When the pull bar 31 has been advanced sufficiently to effect this cocking of the mechanism, it will occupy substantially the position shown in dotted lines in Fig. 1. Having thus cocked the 75 mechanism the pull bar is returned toward its original position, to substantially the position shown in full lines in Fig. 1.

On movement of the pull rod 31, to effect this cocking movement of the carrier arm mechanism the connecting rod 30 will be correspondingly moved to rotate the dog carriers 24 and 36 together, and these will in turn move the ratchet wheels 25 and 38. As the ratchet 25 rotates, the pivot 15 will, under the influence of the friction discs, tend to move in a clock-wise direction. The ratchet wheel 38 is at the same time rotated to move the pins 52. When either of these pins, in their rotation, meets the extension 51, being positively driven it will overcome the friction drive of the disc, and the extension 51 will therefore be moved in a counter-clock-wise direction. If during this rotation of the pivot 15 neither of pins 52 moves into a 90 position to contact with the extension 51, and interrupt its movement, then this pivot will continue to move until the extended end 59 contacts with the stop screw 58, this being the extreme right angular positioning that may be attained, this position being indicated on Fig. 2 of the drawing by means of the dotted line marked A—A. Having assumed this position, it will remain in this position until such time as one of the pins 52 contacts with the extension 51 to rotate the pivot 15 against the action of the friction discs.

After one of these pins contacts with the extension 51 it will rotate the pivot in a counter-clock-wise direction, upon each pull of the operating bar, and on successive movement of the operating rod the pivot will be rotated until the frame assumes extreme left angular positioning, as shown by the dotted lines B—B on Fig. 2. This extreme left angular position is dependent upon the point at which the pins 52 move out of contact with the extension 51. When the cam 55 is brought into contact with the extension 56 110 of the dog 42, and raises that dog from en- 115

gagement with the teeth of the ratchet 38, the ratchet wheel 38 will oscillate back and forth, upon movement of the operating rod, until such time as the dog 42 again comes into contact with the teeth of that ratchet wheel. And under such circumstances the movement of the pivot 15 will be unaffected by the pins 52 during such time as the cam is engaged with the extension 56. By varying the length of the cam the time of holding the dog 36 out of engagement with its co-operating ratchet may be varied as desired. The object of this construction is to break up any rhythm of movement of the pivot 15 which would occur to a degree if the action of the ratchet wheel 38 was not retarded or interrupted. Consequently determinable angles would be thrown. But as the ratchet wheels 25 and 38 are of different diameters the cam 55 is continuously changing its relationship to the pins 52 and the interrupting action may therefore take place when the pivot is in any position.

The angular positioning of the frame, and the carrier arm mounted thereon, and therefore the angle at which the target will be thrown is under latent control, in that while the mechanism is in operation the angular setting of the frame is entirely independent of the control of the operator, and is determined automatically as an inherent characteristic of the mechanism. And because of the indeterminate factors that are introduced, the angular positioning follows no definite sequence whatever, and it is impossible to determine what the next angular positioning will be.

Having thus cocked the mechanism, and at the same time varied its angular position, by pulling upon the operating rod 31 the targets are then placed upon the carrier arm 80, rest against the rubber facing of the rail 81, and supported by the fingers 98.

The attendant then moves the pull rod rearwardly a sufficient distance to bring the extension 95 against the lower portion of the trigger 88. This rocks the trigger about its pivot and moves the latch 86 rearwardly to thus release the carrier arm. Acting under the tension of the main spring 74, the carrier arm will be rapidly swung in a direction opposite to the direction of the cocking movement, and the target or targets, will slide along the carrier arm under the centrifugal force and will be thrown off of the arm at considerable velocity. The length of the carrier arm is so proportioned, with respect to the velocity of this swinging movement, that the targets will travel the entire length of the arm and will be thrown free from the arm, just as the arm reaches a position substantially in alignment with the frame 60.

The movement of the main shaft is stopped by the cam which strikes against the frame. The carrier arm however is loosely mounted

on the main shaft, and its inertia will carry it forward, rotating about the main shaft, until its momentum is overcome by the tension of the spring 82. As the momentum of the carrier arm is absorbed this spring 82 will be wound up, and after the carrier arm has stopped the spring will move it in the reverse direction to bring it back to its normal position.

Mounted in the lower end of the pivot 15 is a stud 100, having a regulating nut 101 and a spring 102 mounted thereon. The spring also bears against a plate 103, the construction being such that by varying the setting of the nut the frictional resistance of the friction discs may be varied as desired.

Only one cam 55 is shown. But if desired a plurality of cams may be used, each of which will introduce still further unknown factors into the operation of the device.

Also, as shown in Fig. 5, the cam 55 may be entirely dispensed with, and in place therefore teeth omitted from the ratchet member 38. Preferably two teeth are omitted, as shown, the device being so arranged that the ratchet will normally be advanced three teeth upon each cocking movement of the trap. By omitting two teeth where a three tooth advance is used, it is obvious that a completely indeterminate factor is introduced.

While the forms of apparatus herein described constitute preferred embodiments of the invention, it is to be understood that the invention is not limited to these precise forms of apparatus, and that changes may be made in either without departing from the scope of the invention which is defined in the appended claims.

What is claimed is:

1. In a target trap of the character described, a base, a frame movable on the base, means for moving the frame in one direction, a rotatable controlling means for moving the frame in the opposite direction and means for varying the rotation of the controlling means.

2. In a target trap, a base, a frame movable on the base, frictional means for moving the frame in one direction, controlling means for overcoming the frictional means, and means for interrupting the action of the controlling means.

3. In a target trap, a base, a frame movable on the base, means for moving the frame in one direction, controlling means for moving the frame in the opposite direction, and means for interrupting the functioning of the controlling means to effect indeterminate positioning of the frame.

4. In an automatic angle trap, the combination of a base, a frame movable on said base, frictional means moving the frame in one direction, and controlling means for moving it in the opposite direction.

5. In a target trap, the combination of a base, a frame movable on the base, frictional means for moving the frame in one direction, and means for intermittently moving the frame in the opposite direction, against the action of the frictional means.

6. In an automatic angle trap, the combination of a base, a frame movable on the base, means for moving the frame in one direction and means for intermittently moving the frame in the opposite direction comprising means to effect indeterminate angular positioning thereof.

7. In an automatic angle trap, the combination of a base, a frame movably mounted thereon, frictional means for moving the frame in one direction, and positively driven control means for moving the frame in the opposite direction, against the action of the frictional means.

8. In an automatic angle trap, the combination of a base, a frame pivoted thereon, frictional means for moving the frame relative to the base, and other frictional means for resisting movement of the said frame.

9. In a target trap, the combination of a base, a frame pivoted on the base, and operating mechanism comprising frictional means for changing the angular positioning of the frame relative to the base, constructed for intermittent operation.

10. In an automatic angle trap, constructed for effecting indeterminate angular positioning of the target throwing mechanism, a base, a frame carrying the target throwing mechanism and movably mounted on the base, and operating mechanism comprising frictional means for varying the angular position of the frame relative to the base.

40 11. In an automatic angle trap, the combination of a base, a frame pivoted thereon, a shaft rotatably mounted within the said frame, a cam carried by the said shaft, a main spring carried by the frame and associated with said cam for actuation thereby, a sliding bar mounted upon said frame and constructed to engage the cam when sliding in one direction to cause energizing of the main spring, and when sliding in the opposite direction to release the main spring.

45 50 55 12. In an automatic angle trap, the combination of a base, a frame pivoted thereon, frictional means for moving the frame in one direction, and positive means for moving in the opposite direction.

60 65 13. In a target trap, the combination of a base, a frame mounted on said base, a target carrier mounted on said frame, a spring for operating said target carrier, a sliding bar carried by the frame, means disconnected from said bar actuated by said sliding bar for energizing said main spring, means carried by the base for moving the said frame relative to the base, and a single means for operating the frame moving means and the

sliding bar to vary the angular positioning of the frame and at the same time energize the main spring.

14. In a target trap, the combination of a base, a frame mounted on said base, a target carrier mounted on said frame, a spring for operating said target carrier, a sliding bar carried by the frame, means actuated by said sliding bar for energizing said main spring, frictional means carried by the base for moving the said frame relative to the base, and a single means for operating the frame moving means and the sliding bar to vary the angular positioning of the frame and at the same time energize the main spring.

70 75 80 85 15. In a target trap, the combination of a base, a frame pivoted thereon, and two control wheels, one adapted to move the frame in one direction and the other to move the frame in the opposite direction.

90 16. In a target trap, the combination of a base, a frame movably mounted thereon, a ratchet disc, friction means connecting said ratchet disc to the frame, a second ratchet disc, means carried thereby for contacting with the said frame for moving the said frame against the action of the said friction means, and means for actuating the two said ratchet discs at the same time.

95 100 105 110 115 120 125 130 17. In an angle trap, a base, a frame movably mounted thereon, friction means for moving said frame in one direction, positive means for intermittently moving the said frame in the opposite direction against the action of the friction means and means for intermittently interrupting action of the said positive means.

18. In a target trap, the combination of a base, a frame movably mounted thereon, friction means for moving said frame in one direction, positive means for intermittently moving the said frame in the opposite direction against the action of the friction means, and means actuated by the said friction means for intermittently interrupting the action of the said positive means.

19. In a target trap, the combination of a base, a frame movably mounted thereon, friction means for moving the said frame in one direction, positive means for intermittently moving the said frame in the opposite direction against the action of the friction means, and a cam carried by the said friction means for intermittently rendering the positive means ineffective.

20. In a target trap, the combination of a base, a frame movably mounted thereon, a ratchet disc mounted on said base, means for imparting to said ratchet disc a continuously progressive rotary motion, friction means connecting said ratchet disc to the said frame whereby movement of the said ratchet disc will effect corresponding movement of the said frame in one direction, a second

ratchet disc, means for moving said ratchet disc in one direction, means for preventing movement of the said second ratchet disc in the opposite direction, means carried by the 5 said second ratchet disc for contacting with the frame to move the said frame against the action of the friction means associated with the first ratchet disc, and means carried by the first named ratchet disc for rendering ineffective the means for reverse movement of the 10 said second ratchet disc during given angular movement of the first named ratchet disc.

21. In an automatic angle trap, the combination 15 of a base, a frame movably mounted thereon, a control wheel adapted to move the frame to different positions, means for rotating said control wheel, and means for automatically rendering such rotating means 20 ineffective, to interrupt the normal motion of the control wheel, whereby the trap will operate to throw targets at indeterminate angles.

22. In an automatic trap, the combination 25 of a base, a frame movably mounted thereon, means for effecting operation of said base to throw targets at indeterminate angles, comprising two control wheels mounted on said base, one of which is adapted to interrupt 30 the normal operation of the other.

23. In an automatic angle trap, the combination 35 of a base, a frame pivoted thereon, operating mechanism for moving said frame to different angular positions, comprising frictional means, target throwing mechanism carried by said frame, a main spring carried by said frame, and actuating means for simultaneously operating the friction means and energizing the main spring.

40 24. In an automatic angle trap, the combination of a base, a frame movably mounted thereon, a ratchet wheel constructed to move the frame in one direction through the instrumentality of friction means, and an 45 additional ratchet wheel adapted to positively move the frame in the opposite direction.

25. In an automatic angle trap, the combination 50 of a base, a frame movable on the base, means for changing the angular positioning of the frame with respect to the base, means for actuating such changing means, and means for temporarily rendering such actuating means inoperative with respect to 55 such changing means for interrupting the functioning of this changing means.

26. In an automatic angle trap, target throwing means, and means independent of the control of the operator of the trap for 60 automatically varying angular positioning of the target throwing means, comprising instrumentalities automatically operating to effect indeterminate positioning of the said target throwing means.

65 27. In a target trap, a base, a frame mov-

able on the base, means for moving the frame in one direction, controlling means for moving the frame in the opposite direction, and means for delaying the functioning of the controlling means to effect indeterminate positioning of the frame. 70

28. In an automatic angle trap, the combination of a base, a frame movable on the base, positively operated means for moving the frame in one direction and means for intermittently moving the frame in the opposite direction to effect indeterminate angular positioning thereof. 75

29. In an automatic angle trap constructed 80 for effecting indeterminate angular positioning of the target throwing mechanism, a base, a frame carrying the target throwing mechanism and movably mounted on the base, and frictional means combined with intermittently operated positive means for 85 varying the angular position of the frame relative to the base.

30. In an automatic angle trap, the combination of a base, a frame pivoted thereon, 90 a shaft rotatably mounted within the said frame, a cam carried by the said shaft, a main spring carried by the frame and associated with said cam for actuation thereby, a sliding bar mounted upon said frame and constructed to engage the cam when sliding 95 in one direction to cause energizing of the main spring, and when sliding in the opposite direction to release the main spring, said bar being mounted for free sliding connection after it has moved the cam to full energizing position. 100

31. In a target trap, the combination of a base, a frame mounted on said base, a target carrier mounted on said frame, a spring for operating said target carrier, a sliding bar carried by the frame, means disconnected from said bar and actuated by said bar for energizing said main spring, means carried by the base for moving the said frame relative to the base, and a single means for operating the frame moving means and the bar to vary the angular positioning of the frame and at the same time energize the main spring, said bar being mounted for free sliding connection after it has moved the cam to 110 full energizing position. 115

32. In an automatic angle trap the combination of a base, a frame movably mounted thereon, a rotatable control wheel adapted to move the frame to different positions relative to the base, and means for interrupting the rotation of the control wheel. 120

33. In an automatic angle trap, the combination of a base, a frame movably mounted thereon, a control wheel mounted on said base, means associated therewith for moving said frame to different angular positions, a second control wheel mounted on said base and adapted to interrupt the normal operation of the first said control wheel. 125 130

34. In an automatic angle trap the combination of a base, a frame pivoted thereon, frictional means for moving the frame in one direction and control means for moving it in the opposite direction, and actuating means for simultaneously operating the frictional means and the control means.
35. In an automatic angle trap the combination of a base, a frame movable on the base, rotatable means for changing the angular positioning of the frame with respect to the base comprising actuating means therefor, and means for effecting the functioning of said actuating means to retard the rotation of the rotatable means.
36. In an automatic angle trap, a base, a frame movable on said base, a main spring, an actuating rod for energizing the main spring, frictional means for moving the frame in one direction with respect to the base and control means for moving it in the opposite direction, and a connecting rod associated with the actuating rod for operating both said means.
37. In an automatic angle trap, a base, a

frame movable thereon, a control wheel, an interrupter wheel, and means for simultaneously operating the control wheel and the interrupter wheel.

38. In an automatic angle trap, a base, a frame movable thereon, a main spring, an actuating rod for energizing the main spring, a control wheel adapted to move the frame to different angular positions in respect to the base, an interrupter wheel, and a connecting rod associated with the actuating rod for operating both the control wheel and the interrupter wheel.

39. In an automatic angle trap the combination of a base, a frame adapted to be moved to different angular positions in respect to the base, a rotatable control wheel for moving the frame in one direction, an interrupting means constructed to interrupt the rotation of the control wheel.

In testimony whereof we hereto affix our signatures, this 29th day of Feb'y, 1924.

GEORGE W. LORIMER.
JAMES McVICKER.
